CLOCK CASING

Frederick Lux, Waterbury, Conn., assignor to Lux
Clock Manufacturing Company, Waterbury,
Conn., a corporation of Connecticut

Application December 14, 1934, Serial No. 757,486

17 Claims. (Cl. 58—54)

This invention relates to clocks, and more particularly to an improved construction for mounting a clock movement in a casing.

One object of this invention is to provide a clock casing consisting of two interfitting telescoping shells which, when assembled, are adapted to hold tightly in proper relation the clock frame, dial, and accessories without the use of screws or nuts.

A further object is to provide a two-part clock casing of the above nature having a supporting base which is adapted to be secured to the assembled casing by nut and screw means.

A further object is to provide a clock casing having exterior ribs adapted to have interlocking engagement with grooves in the supporting base.

A further object is to provide a clock casing of the above nature in which one of the shells is provided with a plurality of locating pins adapted to extend into cooperating apertures in the clock frame for properly positioning said frame when in assembled position.

A further object is to provide a clock casing of the above nature in which the cooperating interfitting shells are provided with interlocking bayonet pin and slot means, and said shells when in assembled position are adapted to press inwardly upon the clock movement to hold it securely in position.

A further object is to provide novel means for attaching the dial backing plate to the clock frame, and for supporting a flat cupped alarm gong therebetween.

A further object is to provide a clock casing of the above nature which will be simple in construction, inexpensive to manufacture, easy to assemble, compact, ornamental in appearance, and very efficient and durable in use.

With these and other objects in view, there have been illustrated on the accompanying drawings two forms in which the invention may be conveniently embodied in practice.

In the drawings:

Fig. 1 represents a front elevational view of the clock casing and base.

Fig. 2 is a side view of the same.

Fig. 3 is a vertical sectional view through the same on an enlarged scale.

Fig. 4 is a front perspective view of the rear casing shell.

Fig. 5 is a rear perspective view of the clock work frame per se.

Fig. 6 is a rear perspective view of the front casing shell.

Fig. 7 is a front elevation of a modified form of

clock casing in which legs are substituted for the base.

Fig. 8 is a side elevation view of the same.

Fig. 9 is a fragmentary vertical sectional view on an enlarged scale, taken along the line 9—9 of Fig. 8, looking in the direction of the arrows.

In the standard type of metal cased clocks now in general use, the clock movement has almost invariably been secured directly to the casing or indirectly thereto by means of supporting brackets. The attachment was usually done by threaded means, such as nuts and screws, and the cost of assembling the movement in the casing was quite high by reason of the fact that the nuts and screws had to be picked up, turned down, and tightened by hand or machine operations. The resulting construction was quite expensive, involving a large number of parts and often requiring special tools to assemble.

By means of the present invention, the above and other disadvantages have been avoided, and a clock construction has been provided eliminating the use of nuts, bolts, or other attaching means between the movement and casing.

Referring now to the drawings in which like reference numerals denote corresponding parts throughout the several views, the numeral 10 indicates generally an ornamental-shaped cylindrical clock casing comprising a circular front shell 11 and a circular rear shell 12, adapted to be telescopically interfitted and enclosing a clock frame 13, within which are the usual escapement controlled time and alarm trains 14. The front shell 11 is provided with an open front 15 through which is adapted to project a concavo-convex glass crystal 16, the edge of which is adapted to rest against the front beveled bezel-like rim 16a of the front shell 11. The front shell 11 is provided with a rear cylindrical rim 17 and has an intermediate raised strengthening rib or bead 18. The front shell is also provided with an outstanding shoulder 16a for keeping the crystal 16 and dial-holding plate 36 in proper position within the clock casing 10.

The rear shell 12 is provided with a back wall 19 having a plurality of properly located apertures 20, through which are adapted to extend the usual arbors carrying the hand setting knobs 21, winding keys 22, and other regulating devices. The apertures 20 for the knobs 21 are preferably large enough to permit the heads of said knobs to pass therethrough upon assembly, while the apertures for receiving the winding keys 22 are just large enough to accommodate the shanks of said keys, it being understood that said keys are

assembled after the casing shells 11 and 12 have been put together.

The forward end of the rear shell 12 is provided with a cylindrical rim 23 adapted to telescope within the rim 17 of the front shell 11. An intermediate raised rib or bead 25, similar to the rib 18 of the front shell 11, is provided on said rear shell 12 and serves as a stop or abutment for the cylindrical rim 17 of the front shell 11 when said shells are in assembled position.

In order to detachably interlock the front and rear shells 11 and 12 with each other, the rim 17 of the front shell 11 is provided with an inwardly projecting radial stud 26, preferably riveted in place, said stud 26 being adapted to engage in a corresponding bayonet slot 27 provided in the rim 23 of the rear shell 12. The lower section of the rim 23 of the rear shell 12 is provided with a radial screw pin 28 projecting outwardly therefrom and having interfitting engagement with a bayonet slot 29 provided in the lower section of the rim 17 of the front shell 11. When the shells have been thus assembled, they are adapted to be supported upon an ornamental flat cupped base 30 having an arcuate upper section 30a for fitting under the assembled shells 11 and 12 of the cylindrical casing 10, as shown in Figs. 2 and 3.

The screw pin 28 previously mentioned is adapted to project downwardly through an aperture 30b provided in the base 30 and receives a binding nut 31. It is to be noted from this construction that when the two shells are assembled with the stud 26 and the screw pin 28 fitted in their respective bayonet slots 27 and 29, and with the base 30 in position, the binding nut 31 serves to lock the base 30 securely upon the casing 10. The arcuate section 30a is also provided with a pair of grooves 30c for fitting over the intermediate ribs 18 and 25, respectively. The separation of the shells 11 and 12 when the base 30 is assembled, will thus be impossible.

In order to properly align the clock frame 13 within the casing 10 to prevent said frame from twisting with respect to said casing, the rear shell 12 is provided with a pair of horizontal aligning pins 32 diametrically positioned with respect to each other, and preferably riveted to the inside of the back wall 19. The forward ends of the pins 32 are provided with reduced shanks 33 which fit into corresponding apertures 34 provided in the rear plate 35 of the clock frame 13.

Positioned in front of the clock frame 13 and spaced therefrom is a backing-up plate 36 for supporting a dial 37, in front of which are the usual hour and minute indicating hands 38 and 39, and an alarm set pointer 40.

In order to rigidly secure the dial-supporting plate 36 to the clock frame 13, provision is made of a plurality of rearwardly projecting flat lugs 41 preferably struck out of the metal of the plate 36, and having reduced rearwardly projecting ears 42 passing through the front plate 43 of the clock frame 13, and bent over therebehind. A relatively shallow cupped gong 44 is positioned between the front plate 43 of the clock frame 13 and the dial-supporting plate 36, and is adapted to be secured in spaced relation from both of said plates by means of a central forwardly offset section 45 spot-welded to the dial-supporting plate 43. The gong 44 is provided with suitable apertures 46 (only one being shown on the drawings), through which the lugs 41 and pointer-

operating arbors 47 may project without touching the gong.

The back wall 19 and the outer edge of the dial supporting plate 36 are made resilient and yieldable and the overall thickness of the movement and crystal is made greater than the normal width of the space between the front and rear walls of the shells 11 and 12. When the shells 11 and 12 are interlocked, the movement and crystal will thus be tightly clamped therebetween by a "cushion" mounting. This will reduce the possibility of breakage of crystals and will compensate for variations in the thickness of the movement, permitting greater tolerances in the manufacture thereof.

The alarm silencing mechanism is preferably located permanently on the back wall 19 of the rear shell 12, and includes a tubular bushing 48 rigidly affixed to the upper section of said wall 19, as shown in Figs. 3 and 4. A plunger rod 49 is slidable in the bushing 48 and carries a handle knob 50 on its outer exposed end and a conical nose 51 on its inner end. By manually pushing in on the knob 50 the conical nose 51 will be caused to engage an alarm stop lever 52 for shutting off the alarm mechanism.

Operation

In the operation of assembling the clock movement in the clock casing, the rear shell 12 will first be positioned horizontally with its open end up in a suitable jig fixture, not shown, which has suitable vertical projections and cavities for the purpose of properly aligning the shell and allowing suitable downward clearance for all the clock movement parts that project beyond the back wall 19.

The clock movement which includes the clock frame 13, dial 37, backing plate 36, gong 44, etc., will then be dropped into position within the casing 10, and by aligning the pins 32 of the rear clock wall 19 with the apertures 34 in the clock frame 13, the movement will be properly located with respect to the shell 12.

The crystal 16 will next be placed upon the dial 37, after which the front shell 11 may be assembled by aligning the radial stud 26 and the bayonet slot 29 thereof with the bayonet slot 27 and the screw pin 28, respectively, of the rear shell 12. The shell 11 will then be telescoped upon the shell 12, and given a slight clockwise twist to interlock the stud 26 and screw pin 28 in their respective bayonet slots.

The clock casing 10 and enclosed movement will then be removed from the jig fixture and inverted. The base will then be placed in position with the pin 28 extending through the aperture 30b in said base 30, and with the ribs 18 and 25 located in the grooves 30c. The nut 31 will then be screwed upon the pin 28 and tightened up.

The final operation in the assembly of the clock is to place the winding keys 22 upon their respective arbors, and screw them up tightly.

Modified form

In the modified form illustrated in Figs. 7, 8 and 9, the construction is identical in all respects to the first form of the invention, except that supporting legs are substituted for the base 30. The rim of the front shell 55 of the modified form is provided with a pair of bayonet slots 56 and 57 adapted to receive a pair of screw pins 58 and 59, rigidly secured to the rim of the telescoping rear shell 60 as by riveting. After the shells 55 and 60 have been assembled in the usual

manner, a pair of hollow tapped ornamental leg members 61 and 62 are adapted to be screwed upon the outwardly projecting threaded sections of the screw pins 58 and 59. The leg members 61 and 62 function in the same manner as the nut 31 of the first form to lock the shells 55 and 60 against relative twisting. The rear shell 60 is also provided with a permanent angular leg 63, preferably formed of sheet metal, and rigidly attached to the wall of said shell 60 as by means of rivets 64. If desired, the leg 63 may be formed in the shape of a curved ornamental scroll as shown in Fig. 8, and it is preferably arranged so that the clock dial will be rearwardly inclined 15 when the casing is set on a horizontal surface.

While there have been disclosed in this specification two forms in which the invention may be embodied, it is to be understood that these forms are shown for the purpose of illustration only, 20 and that the invention is not to be limited to the specific disclosures but may be modified and embodied in various other forms without departing from its spirit. In short, the invention includes all the modifications and embodiments 25 coming within the scope of the following claims.

Having thus fully described the invention, what is claimed as new and for which it is desired to secure Letters Patent is:

1. In a clock, a pair of opposed resilient slightly 30 expandible shell members having telescoping rim sections, means to hold said shell members together, a clock movement held tightly under pressure between said shell members, each of said rim sections having an outwardly extending bead, 35 a base member for supporting said clock on a flat surface, said base member having a recess shaped to fit the lower part of the assembled shell members, said recess being provided with a pair of grooves adapted to fit about said beads, 40 and means for detachably securing said base to the telescoped shell members.

2. In a clock, a pair of opposed resilient longitudinally expandible shell members having telescoping rim sections, means to hold said shell members together, a clock movement held tightly under compression between said shell members, 45 each of said rim sections having an outwardly extending bead, a base member for supporting said clock on a flat surface, said base member having a recess shaped to fit the lower part of the assembled shell members, said recess being provided with a pair of grooves adapted to fit about said beads, and threaded means for detachably securing said base to the telescoped shell members.

3. In a clock, a pair of opposed resilient shell members having telescoping rims and axially expandible end faces, means to hold said shell members together, a clock movement held tightly within 50 in said shell members and compressed thereby, one of said shell members having inwardly extending means for non-rotative engagement with said clock movement.

4. In a clock having a movement and a front 65 crystal, a pair of opposed resilient telescoping casing sections for housing the clock movement and crystal, and means for detachably securing said sections together and simultaneously clamping said movement and crystal under compression therebetween.

5. In a clock, a movement, a casing comprising front and rear telescoping resilient shells for enclosing said movement, means for interlocking said shells, the thickness of said movement being 70 greater than the normal width of the space be-

tween the ends of said shells so that said movement will be held under compression by the resilient shells.

6. In a clock, a movement having a dial plate provided with a yieldable resilient rim, a crystal seated on said rim, a casing comprising a front shell for engaging said crystal and a resilient rear shell engaging said movement, said shells being interlocked telescopically together to hold said movement and crystal tightly compressed therebetween, the resiliency of said dial plate rim and said rear shell providing a cushion mounting for said crystal for preventing breakage and compensating for variations in thickness of said crystal. 15

7. In a clock, a pair of cooperating resilient telescoping casing members, a clock movement held between said members under compression by the pressure thereof without being connected therewith, and means for detachably locking said casing members together. 20

8. In a clock, a pair of opposed resilient shell members having telescoping rims and outwardly expansible end faces, means to hold said shell members together, a clock movement held tightly within and compressed by said shell members, said clock movement having non-twisting engagement with one of said shell members. 25

9. In a clock having an interior movement and a front crystal, a pair of opposed resilient telescopic casing sections for housing the clock movement and crystal, means for detachably securing said sections together and simultaneously clamping said movement and crystal under compression therebetween, and a plurality of leg members projecting downwardly from said casing to support it upon a table or other horizontal surface, said leg members also serving to lock said casing sections together. 30

10. In a clock, a pair of cooperating resilient slightly expandible casing members, means to hold said casing members together, and a clock movement securely positioned in said casing by and between said casing members, the latter members being expanded by engagement with 45 said movement.

11. In a clock, a pair of telescoping resilient shell members, a clock movement held tightly between and under compression by said shell members, and means for detachably interlocking said shell members with each other in expanded condition, said movement having non-rotative interlocking engagement with one of said shell members. 50

12. In a clock, a front shell having a front open face and a rear cylindrical rim, a rear shell having a resilient metallic back wall and a front cylindrical rim for telescopically fitting the rear rim of said front shell, means on said rims for detachably interlocking the shells with each other, an intermediate rib on one of said rims serving as an abutment for the edge of the other rim, and a movement held under compression by and between said shells. 55

13. In a clock casing, a front cup-shaped shell having an open front face and a rear cylindrical rim, a rear cup-shaped shell having a resilient back wall and a front cylindrical rim for telescopic engagement with said rear rim, one of said rims having a raised rib for engaging the edge of the other rim, means on said rims for detachably interlocking said shells with each other, and a movement held under compression by and between said shells. 60

14. In a clock, a clock movement, a casing comprising a pair of front and rear telescoping shells, the front shell having an open face and the rear shell having a closed resilient back wall, means on said back wall extending into said clock movement for non-rotative engagement therewith, and means for detachably holding said shells in tight clamping engagement about said clock movement, said movement being held under pressure by said shells.

15. In a clock, a clock movement, a casing comprising a pair of front and rear telescoping shells, the front shell having an open face and the rear shell having a closed resilient back wall, said back wall having interlocking engagement with said clock movement, and pin and bayonet slot means for detachably holding said shells in tight clamping engagement about said clock move-

ment, said movement being held under pressure by said shells.

16. In a clock, a clock movement, a pair of cooperating telescoping casing members having resilient end sections and surrounding said movement, and means for detachably locking said casing members together to hold the end sections expanded by contact with said movement, whereby said movement is held and clamped therebetween by the pressure thereof.

17. In a clock, a pair of opposed resilient shell members having axially expansible end sections adapted to press upon the opposite faces of a clock movement, and means for detachably connecting said shell members whereby said movement is held and clamped therebetween by the pressure thereof.

FREDERICK LUX.
